VACUUM TYPE CIRCUIT INTERRUPTER

Harold N. Schneider, Springfield, Pa., assignor to General Electric Company, a corporation of New York

Filed Mar. 26, 1959, Ser. No. 802,235

9 Claims. (Cl. 200—144)

This invention relates to vacuum-type circuit interrupter and, more particularly, to an improved shielding arrangement for protecting the insulation of the interrupter against the build-up of metallic coatings thereon.

In a vacuum circuit interrupter, the metallic vapors that are produced by arcing tend to condense on the insulating surfaces of the interrupter and, hence, to form metallic coatings which impair the insulating properties of such surfaces. For protecting these surfaces against such metal deposition, a shielding arrangement of the general type disclosed and claimed in application Serial No. 630,247, Crouch, now Patent No. 2,892,911, filed December 24, 1956, and assigned to the assignee of the present invention, has been found effective. Such shielding arrangement comprises a generally-tubular metallic shield surrounding the arcing gap between the usual electrodes of the interrupter and electrically isolated from both electrodes and from ground. This electrically isolated shield is physically located between the arcing gap and the internal surface of the usual insulating casing for the interrupter and acts to intercept and condense those metallic vapors traveling toward the insulating surfaces from the arcing gap.

The shield can be constructed so that very few of the particles liberated by each interruption reach the internal surface of the casing. But, in some cases, after an extended number of operations, the number of particles reaching the internal surface will become significant. In this regard, deposition of a significant number of these particles results in the build-up of a metallic coating along the internal insulating surface of the interrupter casing. Such coating would reduce the creepage distances present in the interrupter, thus increasing the possibility of a breakdown along the insulating surface. One possible approach toward reducing the possibility of such a breakdown would be to increase the length of the insulating casing so the longer creepage paths would be available to withstand the applied voltage. But this approach is disadvantageous because it involves unduly increasing the overall dimensions of the interrupter and also because it involves exposing the added insulating surfaces of the lengthened casing to metal deposition, unless the metal shield is also lengthened or otherwise reconstructed.

Accordingly, an object of my invention is to construct a vacuum interrupter of this general type in such a manner as to provide increased creepage surfaces, protected from metal deposition, yet without increasing the length of the metal shield or without increasing the length of the insulating casing.

One of the usual steps in the manufacture of a vacuum-type interrupter is a bake-out step in which the interrupter is baked at a relatively high temperature to drive off adsorbed gases and other impurities from the surfaces of its parts. If the shield material is not properly chosen or the shield is not properly handled, there is a possibility that this bake-out step will cause metallic vapors or impurities driven off from the outer surface of the metallic shield to be condensed or deposited on the insu-

2

lating casing of the interrupter. In prior arrangements, such deposition could undesirably decrease the creepage distances available in the interrupter.

Thus, another object of my invention is to mount the metallic shield in such a manner that any metallic vapors or impurities driven off from the outer surface of the shield during bake-out, or during other elevated temperature conditions, do not materially impair the creepage distances present in the interrupter.

5 In carrying out my invention in one form, I provide a highly evacuated envelope comprising a generally tubular casing of insulating material. Disposed within the envelope is a pair of electrodes having a spaced-apart position defining an arcing gap therebetween. A generally 10 tubular metallic shield surrounds the arcing gap and extends for substantial distances on opposite sides of the arcing gap so that its internal surface can intercept and condense metallic vapors travelling from the arcing gap toward the internal insulating surface of the casing. The 15 metallic shield is electrically isolated from both electrodes and from ground and is supported on the casing by means of a generally tubular shield-support of insulating material. This tubular shield-support surrounds the shield and extends along the length thereof between spaced- 20 apart points located near the ends of the shield. The shield is attached to the tubular shield-support, preferably at these spaced-apart points, and the tubular shield-support is attached to the casing at a single longitudinally-restricted location. Aside from at this longitudinally-restricted location, the tubular shield-support is spaced 25 from the casing at all points along the length of the shield-support.

For a better understanding of my invention, reference may be had to the following description taken in conjunction with the accompanying drawing, wherein:

Fig. 1 is a cross-sectional view of a vacuum-type circuit interrupter embodying my invention in one form.

Fig. 2 illustrates a modification of one feature of the interrupter shown in Fig. 1.

40 Fig. 2a illustrates another modification of one feature of the interrupter shown in Fig. 1.

Fig. 3 illustrates still another modified form of the general type of vacuum circuit interrupter shown in Fig. 1.

45 Referring now to the interrupter of Fig. 1, there is shown a highly-evacuated envelope 10 comprising a tubular casing 11 of insulating material, such as a suitable glass, and a pair of metallic end caps 12 and 13 closing off the ends of the casing. Suitable seals 14 are provided 50 between the end caps and the casing to render the envelope 10 vacuum-tight.

55 Located within the envelope are a pair of separable electrodes, or rod contacts, 17 and 18 shown by solid lines in the closed-circuit position. The electrode 17 is a stationary electrode suitably united to the upper end cap 12, whereas the electrode 18 is a movable electrode suitably mounted for vertical movement and projecting through an opening in the lower end cap 13. A flexible metallic bellows 20 interposed between the end cap 13 and the movable electrode 18 provides a seal about the movable electrode and allows for vertical movement thereof without impairing the vacuum inside the interrupter. As shown on the drawing, the bellows 20 is sealingly secured at its respective opposite ends to the 60 electrode 18 and the end cap 13.

65 Coupled to the lower end of the movable electrode 18, I provide suitable actuating means (not shown) which is capable of driving the electrode rapidly downwardly from its solid-line position of Fig. 1 to its dotted-line position to open the interrupter and which is also capable of returning the electrode to the solid-line position to close the interrupter.

When the electrode is driven downwardly to open the interrupter, a circuit-interrupting, or arcing, gap is established between the adjacent ends of the electrodes, and the resulting arc, though quickly extinguished, vaporizes some of the metal of the electrodes.

In order to prevent this metallic vapor from condensing on the internal insulating surfaces of the casing 11, there is provided a metallic shield 25 which corresponds in certain respects to a similarly designated shield in the aforesaid Crouch application. This metallic shield 25 is of a generally tubular configuration and extends along the length of the casing 11 for substantial distances on opposite sides of the gap between the electrodes. The shield 25 is electrically isolated from both of the electrodes 17 and 18 and, preferably, is also isolated from ground, or in other words, is at a floating potential relative to the two electrodes.

For achieving this electrical isolation between the shield 25 and the electrodes, I have supported the shield 25 on the casing 11 by means of a shield-support 27 formed of an insulating material, preferably glass. This shield-support 27, which is preferably of a generally tubular configuration, surrounds the shield 25 and extends along the length of the shield 25 between spaced-apart points located near the opposite ends of the shield 25. At these spaced-apart points, suitable fastening means such as 28 are provided for attaching the shield 25 to the tubular shield-support. In Fig. 1 these fastening means comprise U-shaped metallic finger welded to the outer surface of the metallic shield 25 and crimped around the ends of the tubular shield-support 27.

The tubular shield-support 27 is supported on the casing 11 by attachment means in the form of a joint 30 which constitutes the sole mechanical connection between the shield-support 27 and the casing 11. This joint 30 extends along a single longitudinally-restricted portion of the shield-support 27 substantially shorter in length than the length of the tubular shield-support 27. As a result, the tubular shield-support 27 is spaced from the casing 11 at all points along its length except at the joint 30. Preferably, the joint 30 is located centrally of the length of the tubular shield-support 27.

The parts 27 and 11 can be formed from any suitable combination of structural components fused together at the joint 30. One desirable way of forming these parts is to form the casing 11 and the shield-support 27 each as separate tubular components, which are then telescoped and joined together about the outer periphery of the shield-support by a suitable fusion process which integrally unites them at the joint 30. Another desirable method of construction is to provide two aligned tubular parts, one corresponding to the top half of the shield-support and the casing and the other to the bottom half, and to fuse these two parts together along a horizontally-extending seam at the joint 30.

It will be apparent from Fig. 1 that essentially all straight line paths extending from the general region of the arcing gap to the insulating casing 11 are intercepted by the floating central shield 25. As a result of this relationship, substantially all metallic particles that are liberated from the arcing tips by arcing are captured and condensed either by the shield 25 or by the end caps 12 and 13. A small percentage of these metallic particles can bounce off the metallic parts one or possibly several times before finally adhering, but most of these particles will be captured on the metallic parts before they can reach the internal surface of the insulating casing 11.

Although very few of the metallic particles liberated by each interruption reach the internal surface 31, 32 of the casing 11, the number of particles reaching the internal surface might, in some cases, become significant after an extended number of interrupting operations. In this regard, it will be apparent that such particles would tend to coat this internal surface and thus reduce the length of the creepage paths present in the interrupter.

The term "creepage path," as used herein, denotes the path along an insulating surface over which an electrical breakdown may occur between two conductive members between which voltage exists. The shorter these creepage paths become, the greater becomes the likelihood of an electrical breakdown along the surface.

Because of the particular manner in which my shield 25 is mounted, the interrupter of the present invention has exceptionally long creepage paths in comparison to prior interrupters of equal casing length. More particularly, the creepage path in the disclosed interrupter between the two end caps 12 and 13 does not extend merely along the internal insulating surface 31, 32 of the casing 11 as has been the case in prior interrupters, but in addition extends along the outer surface 33, 34 of the tubular shield support 27. Thus, the minimum creepage path between the two end caps 12 and 13 in the disclosed interrupter is constituted by the sum of the lengths of surfaces 31, 33, 34, and 32. It will therefore be apparent that if any portion of the casing insulating surface does become metallically coated, this coating will be much less likely to cause an electrical breakdown than would be the case with an interrupter having shorter creepage paths. The fact that the outer surface 33, 34 of the tubular shield-support 27 are protected from metal deposition helps to maximize the ability of these surfaces to provide adequate creepage distances after an extended number of switch operations.

The metallic shield 25 of the disclosed interrupter is preferably at a mid-potential relative to the two electrodes 17 and 18 when these electrodes are in their fully open position. This follows from the fact that the gaps separating each end of the shield 25, 28 and the adjacent end cap are of substantially the same size and configuration. These latter relationships would not be materially changed by the presence of a metallic coating on the internal surface of the shield 25, and thus the production of such coatings on the shield 25, as a result of arcing, does not significantly vary the mid-potential relationship of the shield 25 relative to the electrodes.

In accordance with the aforementioned Crouch application, I prefer to construct the interrupter in such a manner that the electric field in the region of the arcing gap is generally symmetrical with respect to a reference plane which bisects the arcing gap between the fully open electrodes and extends perpendicular thereto. Because of the symmetrical relationship of the electrical field about the arcing gap, no significant polarity effect is present, i.e., the gap has substantially the same breakdown strength when subjected to voltage of one polarity as when subjected to voltage of an opposite polarity. Perhaps the most important factor contributing to this symmetrical field relationship is the fact that my shield 25 is at approximately mid-potential relative to the two electrodes 17 and 18 when these electrodes are in their fully-open position. The fact that most of the conductive parts of the switch are generally symmetrical with respect to the above-described reference plane also contributes to the symmetry of the electric field.

It will be apparent that should the position of the shield 25 change for any reason, such changes could affect the potential of the shield and also the configuration of the electric field, causing significant departures from the above-described ideals. An important advantage of my disclosed shield-support 27 is that it is especially well-suited to maintaining the desired position of the shield within close limits. In this regard, it will be noted that the shield-support 27 supports the shield 25 at widely-spaced points near its ends, rather than at a single restricted location. As a result, the disclosed shield-support 27 forms an exceptionally stable mounting for the shield 25.

One of the usual steps in the manufacture of a vacuum-type interrupter is a bake-out step in which the interrupter is baked at a relatively high temperature to drive off adsorbed gases and other impurities from the surfaces of its parts. It is, of course, highly desirable that these

vapors and impurities be prevented from coating the crucial insulating surfaces of the interrupter. The shield-support of the present invention is of considerable assistance in this regard inasmuch as its inner surface 36 serves to capture any particles driven off from the outer surface of the shield 25. The presence of a conductive coating on this surface 36 does not lessen the creepage distances present in the interrupter inasmuch as this surface is already bridged by the conductive shield 25.

Should the shield temperature become elevated for any reason, for example, as a result of an extreme heavy current interruption, it will be apparent that the inner-surface 36 of the shield-support 27 will act in the same manner as described hereinabove to capture particles emitted from the outer surface of the shield 25.

It is to be understood that the fastening means 28 shown in Fig. 1 for connecting the shield 25 to the shield-support 27 is merely illustrative of one embodiment of my invention. For an alternative form of fastening means, reference may be had to Fig. 2, where an annular adaptor 40, S-shaped in cross-section, is used for connecting the shield-support 25 to the shield-support 27. This S-shaped adaptor 40 is welded at one end to the shield 25 and is joined at its other end to the shield-support 27 by being imbedded in the shield-support. The adaptor 40 has a moderate degree of yieldability and, accordingly, allows the shield 25 to expand generally independently of the shield-support 27 during changing temperature conditions. Thus, during bake-out or other high temperature conditions, expansion of the shield 25 does not objectionably stress the shield-support 27.

For another alternative form of fastening means, reference may be had to Fig. 2a. Here an adaptor 40a generally corresponding to the adaptor 40 of Fig. 2 is joined at its outer end to the shield-support 27 by being crimped or otherwise fitted around the outer end of the shield-support 27. This adaptor also has a moderate degree of yieldability for the purpose of allowing the shield 25 to expand and contract generally independently of the shield-support 27 during changing temperature conditions.

Although I prefer to form the casing 11 as a tube of substantially uniform diameter and the shield-support 27 as a centrally expanded tube, as shown in Fig. 1, it is to be understood that these shapes can be materially varied without departing from the broader aspects of my invention. For example, as illustrated in Fig. 3, I prefer to form the casing 11 of certain interrupters with a contracted central region and the shield-support 27 as a tube of substantially uniform diameter. The casing 11 and the shield-support 27 are once again integrally united as by a suitable fusion process.

Another advantage of both of these constructions is that no glass-to-metal seal is required for supporting the shield 25. Eliminating such a seal helps to reduce the cost of the interrupter and also eliminates a possible source of leakage.

The particular interrupters shown and described are merely embodiments of my invention, and it will be obvious to those skilled in the art that various changes and modifications may be made without departing from my invention in its broader aspects. I therefore, intend in the appended claims to cover all such changes and modifications as well within the true spirit and scope of my invention.

What I claim as new and desire to secure by Letters Patent of the United States is:

1. In a vacuum circuit interrupter, a highly evacuated vacuum-tight envelope comprising a generally tubular casing of insulating material, a pair of electrodes located within said insulated casing and disposed in spaced-apart relationship during a circuit-interrupting operation to define an arcing gap therebetween, a generally tubular metallic shield surrounding said arcing gap and extending along the length of said casing for 75 insulating and condensing metallic vapors emitted from said

substantial distances on opposite sides of said arcing gap for intercepting and condensing metallic vapors emitted from said arcing gap, said metallic shield having a potential relative to one of said electrodes in open-circuit position which is a predetermined percentage of the potential between electrodes, said percentage being retained substantially unchanged by the condensation of said metallic vapors on said shield even from a time prior to said condensation, said shield being electrically isolated from both of said electrodes and from ground, a tubular shield-support of insulating material surrounding said shield and extending along a major portion of the length of said shield, means for attaching said shield to said tubular shield-support, means for supporting said shield-support 15 on said casing in spaced-apart relationship relative to said casing in such a manner that the minimum length creepage path between said shield and said electrodes extends along the outer surface of said tubular shield-support for a substantial portion of the length of said shield-support, said interrupter being substantially devoid of solid insulating material located between said arcing gap and said metallic shield.

2. In a vacuum circuit interrupter, a highly-evacuated vacuum-tight envelope comprising a generally tubular casing of insulating material, a pair of electrodes located within said insulated casing and disposed in spaced-apart relationship during a circuit-interrupting operation to define an arcing gap therebetween, a generally tubular metallic shield surrounding said arcing gap and extending for substantial distances on longitudinally opposite sides of said arcing gap for intercepting and condensing metallic vapors emitted from said arcing gap, said metallic shield having a potential relative to one of said electrodes in spaced-apart position which is a predetermined percentage of the voltage between said electrodes, said percentage being retained substantially unchanged by the condensation of metallic vapors on said shield even from a time prior to the condensation of metallic particles thereon, said shield being electrically isolated from both of said electrodes and from ground, a shield-support of insulating material disposed about the outer surface of said shield and extending along a major portion of the length of said tubular shield, means for fastening said shield to said shield-support, attaching means for attaching said shield-support to said casing and constituting the sole mechanical connection between said shield-support and said casing, said attaching means extending along a longitudinally-restricted portion of said shield-support substantially shorter in length than the length of said shield-support and spaced from the ends of said shield-support, said shield being interposed between said arcing gap and said attaching means for protecting said attaching means from the condensation of arc-liberated metallic particles thereon, said interrupter being substantially devoid of solid insulating material located between said arcing gap and said metallic shield.

3. The vacuum circuit interrupter of claim 2 in which said shield-support is of a generally tubular configuration and extends along the length of said shield between spaced-apart points located near the ends of said shield, 60 and in which said means for fastening the shield to said shield-support comprises fastening means located at said spaced-apart points.

4. The vacuum circuit interrupter of claim 2 in which said shield support is of a generally tubular configuration and surrounds said shield.

5. In a vacuum circuit interrupter, a highly-evacuated vacuum-tight envelope comprising a generally tubular casing of insulating material, a pair of electrodes located within said insulated casing and disposed in spaced-apart relationship during a circuit-interrupting operation to define an arcing gap therebetween, a generally tubular metallic shield surrounding said arcing gap and extending for substantial distances on longitudinally-opposite sides of said arcing gap for intercepting and condensing metallic vapors emitted from said

arcng gap, said interrupter having insulating surfaces which when coated with conductive material will form a conductive path which lowers the creepage distance between said electrodes and between said shield and said electrodes, said shield being so located that it is interposed between substantially all of said insulating surfaces and said arcng gap, a shield-support of insulating material disposed about said shield and extending along a major portion of the length of said shield, means for attaching said shield to said shield-support, means confined to a longitudinally-restricted location spaced from the ends of said shield-support for supporting said shield-support on said casing in spaced-apart relationship relative to said casing at all points along the length of said shield-support except at said longitudinally-restricted location.

6. The vacuum interrupter of claim 5 in which said shield-support is of a generally tubular configuration and surrounds said shield.

7. The vacuum interrupter of claim 5 in which said shield-support is of a generally-tubular configuration and extends along the length of said shield between spaced-apart points located near the ends of said shield, and in which said means for attaching said shield to said shield-support comprises fastening means located at said spaced-apart points.

8. The interrupter of claim 5 in which said means for attaching said shield to said shield-support is yieldable to allow for thermally-induced expansion of said metallic shield relative to said shield-support.

9. In a vacuum circuit interrupter, a highly-evacuated vacuum-tight envelope comprising a generally tubular casing of insulating material, a pair of electrodes located within said insulating casing and disposed in spaced-apart relationship during a circuit-interrupting 35

operation to define an arcng gap there-between, a generally tubular metallic shield surrounding said arcng gap and extending for substantial distances on longitudinally opposite sides of said arcng gap for intercepting and condensing metallic vapors emitted from said arcng gap, said interrupter having insulating surfaces which when coated with conductive material will form a conductive path which lowers the creepage distance between said electrodes and between said shield and said electrodes, said shield being so located that it is interposed between substantially all of said insulating surfaces and said arcng gap, a tubular shield-support of insulating material surrounding said shield and extending along the length of said shield between spaced-apart points located near the ends of said shield, means for attaching said shield to said tubular shield-support at said spaced-apart points, means located generally centrally of the length of said tubular shield-support for supporting said shield-support on said casing in spaced-apart relationship to said casing at all points along the length of said shield-support except generally centrally of the shield-support length.
